UNITED STATES PATENT OFFICE.

LOUIS B. SMYSER, OF ELIZABETH, NEW JERSEY, ASSIGNOR TO FERDINAND E. CANDA, OF NEW YORK, N. Y.

IGNITING MECHANISM FOR EXPLOSIVE AND INTERNAL-COMBUSTION ENGINES.

SPECIFICATION forming part of Letters Patent No. 665,037, dated January 1, 1901.

Application filed September 8, 1898. Serial No. 690,530. (No model.)

To all whom it may concern:

Be it known that I, LOUIS B. SMYSER, a citizen of the United States, residing at Elizabeth, in the county of Union and State of New Jersey, have invented certain new and useful Improvements in Igniting Mechanism for Gas, Oil, and other Explosive and Internal-Combustion Engines; and I do hereby declare the following to be a full, clear, and exact description of the invention, such as will enable others skilled in the art to which it appertains to make and use the same.

My invention relates to improvements in igniting mechanism for gas, oil, and other explosive and internal-combustion engines; and it consists in the novel means employed for operating the igniters of a multiple-cylinder engine from a single operating device.

The objects of my invention are, first, to provide a simple and compact mechanism by which the igniters of a multiple-cylinder gas-engine may all be operated by a single operating device having a small amplitude of movement; second, to provide improved means for operating the contact-points of the igniters, and, third, to make the mechanism simple, compact, durable, not liable to derangement, easily assembled and taken apart, and comparatively inexpensive. These objects are attained in the invention herein described and illustrated in the drawings which accompany and form a part of this specification, in which the same reference-numerals indicate the same or corresponding parts, and 35 in which—

Figure 1 is a side elevation of a multiple-cylinder engine of the explosive type provided with my igniting device. Fig. 2 is an end elevation of the engine. Fig. 3 is a longitudinal section of one of the igniters detached from the engine. Fig. 4 is an end elevation looking from the left of Fig. 3 of the igniter, showing particularly the contact-points. Fig. 5 is a detail view of the pawls connected to the movable contact-piece of the igniter and upon the operating-bar by which said movable contact-piece is operated. Fig. 5^a is a detail elevation of said pawls and the bracket on which pawl 22 is mounted, taken from the side opposite to that from which Fig. 5 is taken. Fig. 6 shows a modified construc-

tion of the pawls. Fig. 7, Sheet 1, is a plan view of the cam by which the operating-bar is reciprocated, showing the means employed for varying the point of ignition in each cylinder with reference to the beginning of the stroke. Fig. 8 is a detail view showing the igniters, cam, pawls or catches, and operating-bar of a three-cylinder engine, illustrating particularly the relative arrangement of the pawls or catches upon said bar which is preferred for a three-cylinder engine. Fig. 9 is a view similar to Fig. 8 of the same parts of a four-cylinder engine, showing an arrangement of pawls or catches which may be employed for such an engine. Fig. 10 illustrates a modified arrangement of the springs of the pawls or catches on the operating-bar, and Fig. 11 illustrates a modified arrangement of the cam and operating-bar.

In the drawings, 1 is the main or crank shaft of the engine, and 2 a shaft at right angles thereto, but driven therefrom by gearing having a speed ratio of two to one, as illustrated, and extending to the rear or cylinder end of the engine, where it is connected by gearing to a transverse shaft 3, driven at the same speed as shaft 2, by which the valve-gear of the engine is operated. I will not herein specifically describe this valve-gear, as any suitable valve-gear may be employed. The shaft 2 carries a step-cam 4, by which the operating-bar of the igniting mechanism is reciprocated. 5 is this operating-bar. It is mounted in suitable bearings 6 6, secured to stationary portions of the engine structure and which permit it to reciprocate transversely across the engine. In order to avoid possible rotation of this bar, which might prevent engagement of the pawls or catches by which the several igniters are operated, the operating-bar should preferably have a square or other angular section. The bar 5 is reciprocated by a bell-crank lever 7, pivoted to a stationary portion of the engine-frame and provided at one end with a friction-roller 8, contacting with the face of the step-cam 4, while at the other end it works between collars 9 9 upon the operating-bar 5, or the cam may work directly against the end 10 of the bar 5, as indicated in Fig. 11. A spring 10 causes the bell-crank 7 in the construc-

tion shown in Figs. 2, 8, and 9 and the operating-bar itself in the construction shown in Fig. 11 to press against the cam 4.

Each of the cylinders is provided with an igniter 11, (shown in detail in Figs. 3 and 4,) consisting of a plug 12, adapted to be inserted into an opening in the wall of the engine-cylinder and to be secured therein by suitable bolts and provided with hooks 12, so that when the nuts on said bolts are loosened the plugs may be removed by turning them slightly to one side and then pulling them out. Each plug is provided with two electrical contact pieces or points 13 and 14. Contact-piece 14 is movable, being mounted upon a rock-shaft 17, which has its bearing in a bushing 18, located within an opening in the plug 12, but insulated electrically from the plug by blocks 16 16, of mica or other heat-resisting insulating material. Contact-piece 13 is stationary and forms a part of a pin 15, passing through an opening in the plug 12, and also insulated from the plug by blocks 16 16, of mica or other heat-resisting insulating material.

Upon the outer end of the rock-shaft 17 there is secured a pawl 19, a side elevation of which is shown in Fig. 5. This pawl has a hinged end piece 20, designed to be held normally in the position shown in Fig. 5 by the spring 21, but adapted to move toward the left of Fig. 5, so as to permit a corresponding pawl or catch on the operating-bar 5, which engages with and moves said pawl 19 to the right while the operating-bar is moving to the right, to pass the pawl 19 without operating it upon the return movement of the operating-bar; but the hinged end piece may be upon the pawl of the operating-bar instead, as shown in Fig. 6.

22 is the pawl of the operating-bar which coacts with the pawl 19 of the igniter. It is loosely mounted upon a cylindrical pin 23, carried by a sectional bracket 24, secured to the bar 5. A spiral spring 25 surrounds the pin 23 and is connected at one end to an adjusting-collar 26 and at the other end to the pawl 22 and is arranged to resist motion of the pawl 22 to the left of Fig. 5. A stop-pin 22", carried by the bracket 24 and indicated in dotted lines in Fig. 5, limits motion of the pawl or catch 22 caused by the spring. Another spring 27 surrounds the bushing 18 of the igniter and is attached at one end to an adjusting-collar 28 and at the other end to the pawl 19. The spring 27 resists motion of the pawl or catch 19 toward the right of Fig. 5 and the left of Fig. 4, normally holding the contact-piece 14 out of contact with the contact-piece 13 and in contact with a stop-pin 29, Fig. 4, preferably formed of insulating material or insulated from the plug 12.

The bracket 24 is insulated from the operating-rod 5 by insulating material 24" in order to avoid the passage of an electric current through said rod.

As shown in Figs. 2 and 8, the pawls of the

igniters of the two outside cylinders are arranged to be engaged and vibrated by the corresponding pawls of the operating-bar 5 when said operating-bar is moved to the right of Fig. 2, while the pawl of the igniter of the intermediate cylinder is turned in the opposite direction, being arranged to be operated by its corresponding pawl or catch on the operating-bar 5 when said bar moves to the left of Fig. 2. By operating the igniter of one of the cylinders during the return stroke of the operating-bar the use of an operating-cam 4 having more than two steps is avoided and the amplitude of movement of the bar 5 is made as small as possible.

The two igniters which are operated during the forward or right-hand stroke of the operating-bar 5 are not operated at the same time, the pawl 22 corresponding to the right-hand cylinder being so situated on the bar 5 that it makes contact with its corresponding pawl 19 only when the roller 8 of the bell-crank 7 has mounted the second step 4" of the cam 4, whereas the pawl 22 which causes the operation of the igniter of the left-hand cylinder is so placed that it operates its igniter when the roller 8 has mounted the first step 4' of the cam 4. By moving the pawls 22 to one side or the other, as may be required, upon the bar 5 the point of ignition in each engine-cylinder may be varied as desired without affecting the point at which ignition takes place in the other cylinders.

The operation of the igniting mechanism is as follows: Supposing the engine to be in operation and the shafts 1 and 2 revolving, when the first step 4' of the cam 4 reaches the friction-roller 8 on the bell-crank 7 the operating-bar 5 is moved to the right and the pawl 22 opposite the end of the left-hand cylinder makes contact with the pawl 19 of the igniter of that cylinder, moving it to the right and bringing the contact-points 14 and 13 of that igniting device into contact, so completing a circuit from the electrical generator which supplies current for the engine. As the bar 5 moves onward the pawl 22 slips from under the pawl 19, which latter is then returned to its normal position by the spring 27, the pawl 22 being also returned to its normal position with respect to the bar 5 by its spring 25, and the contact-points 14 and 13 are separated, producing for an instant a spark, which ignites the explosive charge in the engine-cylinder. When the roller 8 encounters the second step 4" on the cam 4, the rod 5 is moved still farther to the right, and the igniter of the right-hand cylinder is operated in a similar manner. When the time for an explosion in the third or intermediate cylinder has nearly arrived, the cam 4 permits the spring 10 to pull the rod 5 to the left, and the igniter of the intermediate cylinder is operated, the pawls 22 of the two outside cylinders at the same time passing their corresponding pawls 19 by pushing aside the hinged sections 20 of said pawls.

If the engine have four cylinders, with valve-gear arranged to produce an explosion every half-revolution of the crank-shaft of the engine, then the arrangement of igniter-pawls shown in Fig. 9 may be employed, the igniters of two of the cylinders being operated during the forward stroke of the bar 5, the other igniters being operated successively on the back stroke. The cam 4 then has two intermediate steps 4', one on each side of the second or highest step 4".

As already stated and as shown in Fig. 6, the hinged section 20, which permits the pawl 22 to pass the pawl 19 during the reverse movement of the operating-bar 5, may be on pawl 22 instead of on pawl 19. In this figure pawls 19' and 22' correspond, respectively, to pawls 19 and 22 of Figs. 3 and 5; but the hinged section 20', corresponding to section 20 of Figs. 3 and 5, is mounted upon pawl 22', as is the spring 21' of said hinged section. The section 20' is arranged to swing in the direction opposite to section 20.

The spring of the pawl 22 instead of being mounted as shown in Fig. 3 may be a tension-spring 25', secured to the pawl, which in this case may have the form of a bell-crank lever, and to an extension 24' of bracket 14, arranged as shown in Fig. 10. The pawl 22 is free to move in either direction against the tension of the spring, so that it is not necessary that the pawl 19 should have a hinged section 20', as in the construction shown in Figs. 5 and 6.

An important feature of my invention is the means employed for varying the speed of the engine, as may be desired. This is done by varying the point at which ignition takes place in each cylinder with reference to the beginning of the stroke in that cylinder. As is indicated in dotted lines in Fig. 7, the shaft 2 at that point where the cam 4 is mounted is provided with a spiral keyway. A pin secured to the cam 4 and fitting into this keyway constitutes the driving connection between the shaft and cam. The cam has a hub 30, in which is a groove 31, (shown in Fig. 1,) and a pivoted lever 32, having a pin fitting into said groove, serves as a means for shifting the cam laterally along the shaft 2, thereby varying its angular position on said shaft, and so varying the point at which ignition takes place in the several cylinders.

The various igniting devices may be removed from their respective cylinders for the purpose of cleaning the contact-points by loosening the bolts which hold the plugs 12 in their holes in the walls of the engine-cylinders and then turning said plugs slightly and pulling them out.

Having thus completely described my invention, what I claim, and desire to secure by Letters Patent, is—

1. In an igniting mechanism for multiple-cylinder explosive-engines, the combination, with a reciprocating operating member, and

a plurality of igniters arranged to be operated by said operating member during each motion thereof in one and the same direction, of coacting pawls or catches on the several igniters and on the operating member, the catches on the operating member being spaced differently from the catches on the igniters, and a step-cam for reciprocating the operating member.

2. In an igniting mechanism for multiple-cylinder explosive-engines, the combination, with a reciprocating operating member, of a plurality of igniters, and coacting pawls or catches on the operating member and on the igniters, arranged to permit the pawls on the operating member to pass by the corresponding pawls of the igniters, after operating said igniters, one of the pawls of each pair being provided with a yielding member adapted to permit the passage of its companion pawl without operating the igniter during the return movement of the operating member, the pawls on the operating member being spaced differently from the pawls on the igniters, whereby the igniters are operated successively as the operating member reciprocates.

3. In an igniting mechanism for multiple-cylinder engines, the combination, with a plurality of igniting devices, of a reciprocating operating member, and coacting pawls or catches on the several igniting devices and on the operating member, the catches on the operating member being spaced differently from the catches on the igniting devices, and the catches corresponding to one of the igniting devices being reversed so that said igniting device is operated on the return movement of the operating member, and a step-cam for reciprocating said operating member.

4. In an igniting mechanism, the combination, with an igniting device, of a reciprocating operating member, and coacting pawls or catches on the igniting device and operating member by which said igniting device is operated as the operating member reciprocates, the pawl or catch on the reciprocating operating member being insulated from the main portion of the engine.

5. In an igniting mechanism, the combination, with an igniting device having insulated contact-pieces, one of which is movably mounted, of a reciprocating operating member, and coacting pawls or catches on the movable contact-piece and on the reciprocating operating member, by which said movable contact-piece is operated as the operating member reciprocates, the pawl or catch on said operating member being insulated from the main portion of the engine.

In testimony whereof I affix my signature in the presence of two witnesses.

LOUIS B. SMYSER.
